(57) **CLAIM**

The ornamental design for a watch, as shown and described.

DESCRIPTION

FIG. 1 is a side elevational view of a watch showing my new design, the opposite side being a mirror image thereof;

FIG. 2 is a end elevational view of a first end thereof;

FIG. 3 is a bottom plan view thereof;

FIG. 4 is a top plan view thereof;

FIG. 5 is a perspective view of the bottom and said first end thereof; and,

FIG. 6 is a perspective view of the top and said first end thereof.

The views in the drawings are shown on different scales.
